UNITED STATES PATENT OFFICE

EARL E. CRONENWETH AND CHARLES G. HAMER, OF SAN FERNANDO, CALIFORNIA

SPRING OILER

Application filed May 13, 1930. Serial No. 451,983.

This invention relates to an oiling device for springs of vehicles, and is particularly adaptable to oiling leaf springs used in the construction of automobiles.

The primary object of the invention is to provide a casing for enclosing the spring having a suitable reservoir in association with the casing for containing a lubricant which is supplied to the spring by the bounding of the automobile, during its passage over the road.

Further objects of the invention are to provide a spring oiler of the character referred to that is strong, compact and durable, thoroughly reliable for its intended purpose, very simple in its method of assembly, and comparatively inexpensive to manufacture and install on all standard types of automobiles.

With the foregoing and other objects in view, the invention consists of a novel construction, combination and arrangement of parts as will be hereinafter more specifically described and illustrated in the accompanying drawings, wherein is disclosed an embodiment of the invention, but it is to be understood that changes, variations, and modifications, may be resorted to without departing from the spirit of the claim hereto appended.

In the drawings wherein like reference characters denote corresponding parts throughout the several views:—

Figure 1 is a side elevation partly in section of the spring suspension of an automobile, showing the spring oiler of the present invention applied thereto,

Fig. 2 is a detailed longitudinal vertical section through the spring oiler,

Fig. 3 is a detailed vertical section through the oiler taken substantially on the line 3—3 of Fig. 2.

In the drawings wherein for the purpose of illustration is shown the preferred embodiment of our invention, 4 indicates one side rail of a chassis frame of an automobile. To the one end of the chassis frame 4 is pivoted one end of the longitudinal leaf spring 5 on the pin 6. The other end of the spring 5 is pivotally connected to the lower ends of

the links 7 by the pin 8, and the upper ends of the links are pivoted to an intermediate portion of the side rail 4 by the pin 9.

A transverse axle 10 is anchored to the middle of the leaf spring 5 in any conventional manner.

There are two spring oilers indicated generally at 11, 12 disposed one to each side of the axle 10 and terminating at their outer ends adjacent the opposite ends of the spring.

Each spring oiler A, B is formed in the same manner and it is believed that a description of the one, will clearly teach the construction of the other.

Each oiler consists of a substantially U-shaped top section 11 and a bottom section 22 interfitting within the top section, the sections when in interfitting relation, conformably fitting the top, bottom and sides of one half of the spring 5. The U-shaped bottom section 22 has the free edges of its sides 14, 15 tapering upwardly and rearwardly so as to accommodate the configuration of the spring, the said spring being thicker at the center than it is at its ends.

The top section 11 has its sides tapering in the same manner and the sides 12, 13 of said top section overlap the sides 14, 15 of the bottom section as suggested in Fig. 3.

Across the inner face of the crown 16 of the top or cover section, at the deep end thereof is a strip of felt 17 for absorbing lubrication, and also closing the space between the top of the spring and the crown of the cover or top section.

There is likewise a strip of felt 18 in the crown at the other end of the cover for the same purpose as the strip 17.

Across the inner face of the crown of the bottom section at the deep end of said bottom section is a felt strip 23 which serves the same purpose as, and is in alinement with the felt strip 17. There is also a felt strip 24 across the inner face of the crown of the bottom section at the shallowest end thereof, which is in alinement with the felt strip 18 on the cover section.

Intermediate the ends of the oiler, the bottom wall of the bottom member or section of the oiler is formed with a well 25, and the

bottom wall of the bottom section opposite the well is provided with suitable openings for a purpose hereinafter made manifest.

Arranged within the bottom section and 5 extending across the bottom wall thereof, is a strip of felt or other suitable absorbing material M for disposition between the bottom wall of said bottom section and the bottom of the spring.

10 One or more wicks W extend upwardly from the well, through the openings in said bottom wall to merge with the felt pad M, whereby oil is drawn from the well by capillary attraction into the oiler to be absorbed by the felt pad M.

15 A nozzle fitting 26 is anchored to one of the side walls of the well 25 for the purpose of introducing lubricant into the well. This nozzle is preferably provided with a 20 check valve outwardly to prevent the lubricant escaping from the well.

Secured to the outer face of the crown of the bottom section 22 adjacent one end thereof, is a yoke 27 having lateral outstanding 25 hooks 28, 29 at its ends which are in alignment with the hooks 20, 21 of the yoke 19 on the top of the device. Coil springs 30, 31 have eyelets 32 on their opposite ends to engage with the lateral hooks on the sides 30 of the cover and bottom sections for holding said sections together about the spring 5.

The outer end of each of the devices is held in place by the clip and its bolts shown generally at 34.

35 Thus, it will be seen that we have provided a very simple detachable spring oiler having means at its opposite ends to prevent the escape of lubrication, and each section of the oiler is preferably formed of a rigid metal so as to be strong and durable.

40 The present embodiment of the invention has been disclosed in considerable detail merely for the purpose of exemplification, since in actual practice it attains the features of advantage enumerated as desirable 45 in the statement of the invention and the above description.

It is to be understood that by describing in detail herein any particular form, structure or arrangement, it is not intended to limit the invention beyond the terms of the claim or the requirements of the prior art.

Having thus described our invention, what we claim as new is:—

55 In a spring oiler, a casing open at its opposite ends adapted to receive a leaf spring extending therethrough, said casing comprising a top section, a bottom section, said sections being substantially channel-shaped in 60 cross section, the sides of one of said section being arranged in overlapping relation with respect to the sides of the other of said section, means at the ends of the section to prevent the escape of lubricants, said bottom section formed with a lubricant well

having communication with the interior of the bottom section, a lubricant absorbing pad arranged in the bottom section for substantially the full length of said section, wicks extending from the well into said bottom section to merge with said absorbing pad, a clamp overlapping the sections at one end, and co-acting retractile means on the other end of the sections for holding said sections together.

70 In testimony whereof we affix our signatures.

EARL E. CRONENWETH.
CHARLES G. HAMER.
